(57) **CLAIM**

The ornamental design for portable plastic store bag holder for trash receipt, as shown and described.

DESCRIPTION

FIG. 1 is a perspective view of the first embodiment of a portable bag holder of this design with a mounted plastic bag shown in phantom lines;

FIG. 2 is a top plan view of this design;

FIG. 3 is a front elevational view of the first embodiment;

FIG. 4 is a side elevational view of the first and second embodiments of this design;

FIG. 5 is a rear elevational view of the first embodiment;

FIG. 6 is a bottom plan view of the first embodiment;

FIG. 7 is a perspective view of the second embodiment of this design;

FIG. 8 is a front elevational view of the second embodiment;

FIG. 9 is a top plan view of the second embodiment;

FIG. 10 is a rear elevational view of the second embodiment; and,

FIG. 11 is a bottom plan view of the second embodiment of the plastic bag holder of this design.
